UNITED STATES PATENT OFFICE.

GUIDO HORN, OF WEISSENSEE, NEAR BERLIN, GERMANY.

CIRCULAR-BRAIDING MACHINE.

Application filed June 11, 1917. Serial No. 174,142.

(GRANTED UNDER THE PROVISIONS OF THE ACT OF MARCH 3, 1921, 41 STAT. L., 1313.)

To all whom it may concern:

Be it known that I, GUIDO HORN, a citizen of the German Empire, residing at Weissensee, near Berlin, in the Kingdom of Prussia, 5 Germany, have invented certain new and useful Improvements in Circular-Braiding Machines (which has been patented in Germany on an application filed March 9, 1916, Patent No. 320,100, and in Great Britain 10 filed March 1, 1917, Patent No. 164,759 of 1921, and also in Austria filed April 12, 1917, Patent No. 88,101); and I do hereby declare the following to be a full, clear, and exact 15 description of the invention, such as will enable others skilled in the art to which it appertains to make and use the same.

Reference is to be had to the accompanying drawings in which:

Fig. 1 illustrates in elevation two thread 20 guiding levers of my improved machine and the curved cam by which they are controlled, Fig. 2 is a diagrammatic view of the paths followed by the threads under the influence of said thread guides. Figs. 3 and 4 illustrate sample fabrics which may be produced 25 by my improved machine; and Fig. 5 shows a portion of a machine embodying this invention.

My invention shown in British Patent 30 164,759 of June 3rd, 1921, is to be applied to existing braiding machines of the type as shown in my British Patent 26,464 of 1913 in which the guides for the outer threads are so controlled by means of a cam that a 35 fabric is formed as illustrated in Fig. 3 and which I shall term a "two-over-two-fabric". In many cases, it is desirable to make by these machines, similarly as by bobbin machines, a fabric in which two adjoining 40 outer threads are so guided into the fabric that both pass over and under the same inner threads, so as to form what may be termed a "one-over-one-fabric", as in Fig. 4 such fabric being a "two-and-two-fabric" 45 according to its formation.

The existing circular braiding machines have two-armed or one-armed thread-guiding levers by which all the outer threads are successively guided along the same path. In 50 order to obtain a "two-and-two-fabrics", it is indispensable that the threads should alternately move along two distinct paths, unless the unsatisfactory expedient of passing two adjoining threads through the same

guiding lever, is resorted to. To provide 55 two cams for the purpose described, would be inconvenient as it would render the machine complicated and expensive.

According to my invention, I provide a single cam co-operating with alternately arranged two-armed and one-armed thread-guiding levers by which means I am able 60 to device two distinct movements of the thread from only one cam.

Referring now to Figs. 1 and 5, 1 is a two- 65 armed, and 2 a one-armed thread-guiding lever. The next lever to the right of Fig. 1 would be a two-armed one, the next to that a one-armed one, etc. The levers are pivotally carried on standards 3 and 4, respectively, and provided with rollers 5 and 6, respectively. In lever 1, the roller 5 and the thread eye 7 are on opposite sides of the pivot 8 of that lever, while the roller 6 of lever 2 is between the pivot 9 and the eye 10.

Both rollers 5 and 6 engage a cam 11 by 70 which the levers 1 and 2 are so guided that the eyes 7 of all the levers 1 follow the dotted line *a* in Fig. 1, while the eyes 10 of levers 2 follow the full line *b*.

Referring now to Fig. 2, the desired "two-and-two-fabric" is hereby formed as follows: The thread of guiding lever 1 follows 75 the dotted curve *a* and, in doing so, successively passes over bobbins I and II, under bobbins III and IV, over the two succeeding bobbins, etc., the bobbins moving from the right to the left in Fig. 2. The thread from lever 2 is guided over and under the same 80 bobbins as that from lever 1. It follows the curve *b* and therefore passes over bobbins I' and II', under bobbins III' and IV', over the two succeeding bobbins, etc. This 85 causes the two threads or sets of threads to be so placed in juxtaposition as if they had come from a common bobbin. The succeeding threads being thus worked into the fabric in pairs, the desired "two-and-two-pattern" is produced.

I desire it to be understood that I may, if desired, arrange my one-and-two-armed thread-guiding levers in any relation different from the one described so as to produce 90 different patterns, without departing from the spirit of my said invention.

I claim:

1. In a circular braiding machine having

two sets of bobbins movable in opposite directions, thread guiding levers co-operating with said bobbins, and a common cam for controlling all said levers, half of said levers being one-armed, and half of them being double-armed, said one-armed and double-armed levers being alternately arranged.

2. In a circular braiding machine having two series of bobbins which revolve in opposite directions, two sets of thread guiding levers therefor, one set being single-armed

and the other being double-armed, arranged alternately and of the same effective length, in combination with a single cam guide engaged by all of the levers so that two consecutive threads are laid along distinct but similar thread tracks for braiding their threads in the same braid. ¹⁵

GUIDO HORN.
